UNITED STATES PATENT OFFICE.

JOHN PUHL, OF CHICAGO, ILLINOIS, ASSIGNOR TO THE JOHN PUHL PRODUCTS CO., OF CHICAGO, ILLINOIS, A CORPORATION OF ILLINOIS.

DESIGN FOR A BOTTLE.

Application filed August 7, 1926. Serial No. 18,626. Term of patent 3½ years.

To all whom it may concern:

Be it known that I, JOHN PUHL, a citizen of the United States, residing at Chicago, in the county of Cook and State of Illinois, have invented a new, original, and ornamental Design for Bottles, of which the following is a specification, reference being had to the accompanying drawing, forming a part thereof.

On the drawing:

Fig. 2 is a side elevation thereof.

I claim:

The ornamental design for a bottle, as shown.

JOHN PUHL.
